UNITED STATES PATENT OFFICE.

FELIX GUSMAN AND MARIE ALICE GUSMAN, OF CAIRO, EGYPT.

APPARATUS FOR DISPLAYING ADVERTISEMENTS.

Application filed May 15, 1925, Serial No. 30,486, and in France May 21, 1924.

This invention relates to a process of exhibition of texts or pictures, for advertising and similar purposes, by means of flat-display appliances with complete disappearance 5 of the exhibits.

Appliances as used heretofore for the purpose did consist of frames of fixed dimensions, where the texts, etc., were caused to appear and disappear in a field of limited, 10 invariable size, this being done by various suitable means. Owing to this feature, the public soon becomes accustomed to such devices, and a rapid decrease in their efficiency is the consequence.

15 On the other hand, in the process which forms the matter of this invention, the text or picture is displayed suddenly or gradually, thus causing, so to speak, a "visual shock" to the public, which commands attention and excites the curiosity of the public; after which the text or picture disappears entirely, so that the following re-appearance will benefit by the same effect of suddenness and surprise.

20 25 The apparatus used for performance of this displaying process substantially consists of a base, a movable body which can recede away from this base whilst remaining parallel with it, flexible walls, which can unroll or spread out between said base and said movable body, and a suitable mechanism that causes said movable body to move away from said base, thus displaying the flexible surfaces.

30 35 Various forms of execution of this invention are shown in the accompanying drawings, in which similar parts are always represented by the same respective reference numbers.

40 45 In Figs. 1 and 2 is shown a device with two display surfaces, latter being shown here in the "displayed" position. Figs. 3 and 4 are outside views of the same device, in the "collapsed" position. Fig. 5 refers to a device which operates on the same general lines, but where a number of flexible surfaces can be alternately displayed on both sides. Fig. 6 is a view in side elevation of the lower portion of the structure shown in 50 Fig. 5, a part of the casing 1^a being removed.

In these drawings, 1 is the base of the apparatus; 2 is the movable part or body.

55 The relative motion of latter with respect to the base is effected by means of a set of hinged parallelograms, consisting of bars

or links 3 and 4; the deformations of these parallelograms can be effected by the operation of handles 3' and 4', which extend through the walls of the base 1. When these 60 handles or levers are operated, this causes part 2 to move towards base 1 or away from this base, whereas both parts will permanently remain parallel with each other, because the pivots 5 and 6, which are fastened 65 to the links 3 and 4, can slide freely within the slots 7 and 8 of both base and movable part. It will be readily understood that part 2 will move towards base 1 when pulling apart the handles 3' and 4' and, 70 reversely, will move away from said base when pulling together said handles.

In the Figures 1 to 4, the flexible walls or surfaces 9 and 10 are fastened by one of their ends to part 2, and by their other ends to 75 rolls 11 and 12, which are so-called "automatic" rollers, that is, provided with springs (internal as a rule) said springs being so arranged as to cause the rolls to have a tendency to wind up the corresponding flexible 80 surfaces.

Thus, the flexible surfaces which bear the advertising texts or pictures or the like, which are to be exhibited, can be displayed integrally or partly, suddenly or gradually, 85 and at such intervals as will be found desirable, at will of the operator who actuates the handles 3' and 4'.

In the alternative form shown in Fig. 5, there are several flexible surfaces (four in 90 the sketch) provided on each side of the parallelogram set. Said surfaces, 9^a and 10^a, are so arranged as to wind up on "automatic" rolls 11^a and 12^a; the shafts of said rollers, numbered 13 and 14, are carried by 95 cheeks 15 and 16, which in turn are seated on both ends of shafts 17 and 18. There are suitable notches 19 and 20 provided on the periphery of said cheeks 15 and 16, and the "free" or "upper" ends of the flexible 100 surfaces are fitted with rails or rods 21 and 22, which can rest in said notches; said rods project outwards, over the edges of said cheeks, so as to permit them being gripped on both ends by hooks 23 and 24, which are 105 pivoted to part 2^a and fitted with springs 25 and 26, said springs being so arranged as to always maintain the hooks in the position shown on the drawing.

It is to be understood that each shaft 17 110 and 18 carries at each end a roll-carrying plate or "cheek" 15, and 16, and that these

shafts extend across the base from end to end in a direction at right angles to the paper in Figure 5. The dotted lines extending upward on each side of Figure 5 indicate the positions which the flexible bands would occupy when on exhibition.

Furthermore, each of the shafts 17 and 18 carries on one of its ends a ratchet wheel 27. A pawl 28 pivotally supported upon a standard carrying the shaft 18 is engaged with the teeth of said wheel 27, by means of a spring 29. Said pinion 30 is mounted loose on the corresponding shaft 17 or 18, and meshes with a rack 31, which slides in a guide 32, and is so arranged that it is lowered by part 2^a on completion of the downwards stroke of said part, and then pulled upwards by the spring 38.

The fixed base 1^a is also provided with fingers or cams 34 and 35, which are arranged so as to cause the hooks 23 and 24 to release, when said cams strike the pins 36 and 37 of the hooks.

Operation.—Let us examine a complete cycle of operation, starting from the position shown on Fig. 5; i. e., where there is one of the flexible surfaces displayed on each side of the device. If the operator gives up exerting a pull on the handles, the automatic rolls will wind up the flexible surfaces, so that part 2^a will move towards base 1^a.

As soon as the pins 36 and 37 strike the cams 34 and 35, the hooks 23 and 24 will release the ends of the rods 21 and 22, and said ends will fall into the notches 19 and 20 of the cheeks 15 and 16. As soon as this is done, and during the last part of the downstroke of part 2^a, said part 2^a strikes the rack 31, thus rotating the pinions 30;

finally, the motion of the rack will cause the shafts 17 and 18 to revolve a quarter of a turn in the directions shown by the arrows a, after which these shafts will be maintained by the pawls 28 in the position which corresponds to other rolls or flexible advertisements. At that time, the hooks 23 and 24 have come back to their initial positions, so that they will grip the ends of the rods, and thus unwind and display a set of two new advertising surfaces, as soon as part 2 will be operated upwards again.

What we claim is:

1. Means for displaying advertisements and the like comprising two parallel spring rollers, lifting means located between said rollers, a body adapted to be raised by said lifting means, and flexible bands attached to said rollers and to the two sides of said body whereby a balanced tensional resistance is produced during the simultaneous display of two advertisements.

2. Apparatus for displaying a number of different advertisements successively comprising a plurality of spring rollers mounted rotatably in parallel position, a flexible band on each, a lifting body, means for raising and lowering said body, means automatically actuated by movements of said body for rotating the mounting of said bands and automatic means on said body adapted to release and engage the ends of the different bands successively as said body is raised and lowered.

In testimony whereof we affix our signatures.

FELIX GUSMAN.
MARIE ALICE GUSMAN.
